ARTIFICIAL TEETH AND BACKING THEREFOR

Charles K. Peck, New York, N. Y.

Application January 29, 1948, Serial No. 5,127

5 Claims. (Cl. 32—9)

1

This invention relates to improvements in artificial teeth and backing therefor. It, more particularly, has to do with a type of novel construction that can be utilized in the initial fabrication of a unitary bridge and wherein other teeth may be replaced or interchanged in lieu of the original or previous ones used. The teeth and backings of this invention have certain advantages when employed in fixed bridgework and are likewise advantageous when used in association with the various kinds of removable bridgework.

Heretofore the metal framework of dental bridges has commonly been composed of various kinds of golds or stainless steels but there has been a long felt need for a combination and design of structures that would give adequate strength while keeping down the display of metal viewable from the labial side of the bridge. This unsightly display has been especially observed in the contact areas, in between the teeth, at the incisal edges or on the occlusal surfaces when the patient's mouth was open as in laughing or talking. Further, there has long been a need for a tooth structure of sufficient bulk and thickness to nullify any influence of the backing reflecting through the tooth structure or otherwise adversely effecting the shade or color of the tooth, such shortcomings have not permitted the tooth to have its intended values in shade control and translucency. Moreover, there has been a need for a replaceable tooth that would be more sanitary or hygienic while in service in the mouth; also, a tooth that would give efficient service and would not become objectionably discolored due to the washing out of dental cements and the ingress of stains such as may be caused by tobacco or certain medicines and the like. The space created by the disintegration of cement also creates a harbor for decomposing food particles and for bacteria which can adversely affect the state of health of the patient besides creating an offensive bad breath toward others. The bacteria can be pathogenic or non-pathogenic but if pathogenic they may invade the human body by way of the blood stream or through the digestive tract.

Replaceable teeth of the prior art have frequently broken either because of their inherent weakness, because of the disintegration of the dental cement, or because the teeth were not designed for universal use in all sections of the mouth and for all kinds of bites for which the dental practitioner produces bridges. Such breakages of teeth are not only embarrassing to the patient, but their loss from the bridge im-

2

pairs the efficiency of mastication for the period of time they are out and also present a certain amount of inconvenience, loss of time and added expense to the patient in having the repairs made.

A certain amount of artificiality has been common heretofore in bridges where teeth of commercial dental manufacturers have been used. The unharmonious appearance sometimes could be traced to improper tooth form or sometimes to improper shades or to the improper amount of translucency and the like when such teeth of commercial manufacture were compared with the remaining natural teeth of a patient. This has brought a long felt need for a tooth structure that could be fabricated in a "tailor-made" fashion as it were by the dentist or the dentist's mechanical technician for each individual patient. Under such conditions of fabrication, the dentist can conduct certain fact-finding observations of the patient's natural teeth and can virtually write a prescription whereby the teeth of the bridge structure will harmonize and precisely simulate the natural teeth in form, characterization, shade, translucency and the like. While I am aware that certain materials have been used and certain technics have been advanced in dentistry heretofore whereby a certain elementary approach to "tailor-made" teeth has been accomplished, yet these materials and technics have fallen far short of the professional needs.

In my improved artificial tooth structure and the backing mount, which constitute the present invention, I have overcome all of the above shortcomings of the prior art and I have provided certain effectual advantages that will be herein-after explained in detail.

One of the objects of my invention is to provide a dental bridge consisting of an assembled metal framework, a portion of which is one or more of my metal backing mounts, and one or more artificial teeth composed of a suitable plastic and formed in fixed relation on the mounts of the framework.

Another object of my invention is to provide an improved backing mounting means for supporting my plastic tooth invention.

Another object of my invention is to provide backing mounts in assorted widths and lengths whereby the encompassing backing member may be adjustably bent to accommodate minor variations in tooth width.

Another object of my invention is to provide preformed plastic teeth of a kind, shape and shade than can be used to replace any tooth

member previously employed on the bridge whether the bridge is or is not anchored in the mouth of the patient.

Another object of my invention is to provide plastic teeth of the type described in various sizes and shades as articles of manufacture.

In the drawings:

Fig. 1 shows an elevational end view of the pair of dies and punch I use in the process of bending my curved backing;

Fig. 2 is a plan view of the first step in making my curved backing;

Fig. 3 is an elevational side view of the tenon (post, rib and lugs) that forms a part of my completed curved backing;

Fig. 4 is a front elevational view of the parts shown in Figs. 2 and 3 when in assembled order;

Fig. 5 is an edge elevational view of the backing of Fig. 4;

Fig. 6 is a similar view of my completed curved backing after the backing shown in Fig. 5 has passed through the dies and punch assembly shown in Fig. 1;

Fig. 7 is a side elevational view of a posterior (bicuspid) tooth made in accordance with this invention;

Fig. 8 is an elevational lingual view of the tooth illustrated in Fig. 7;

Fig. 9 is a horizontal cross-sectional view of the tooth when viewed downwardly along the plane of the line 9—9 of Fig. 8;

Fig. 10 is a perspective view of a dental bridge wherein two of my backings, according to Fig. 6, are shown.

My improved backing is made preferably from a precious metal alloy, although it may be composed of any other suitable material. The backing is formed from sheets of the selected metal, which advantageously possess a thickness of the order of .012 to .018 of an inch. Such a sheet is passed through suitable blanking and punching dies, not shown, to produce therefrom a plurality of flat, rectangular or square blanks of metal of the character shown at 1 in Fig. 2, which blanks possess required dimensions. Then, either by the blanking operation or by a separate operation, I punch one or more aligned holes 2 through the blank along its axial center line.

The tenon 3, shown in Fig. 3, is usually made of the same alloy as that used in the blank of Fig. 2 and is preferably T-shaped in transverse cross section. It may be of solid construction or of sheet-folded hollow construction. If of solid construction, it may be made by rolling, drawing or swaging, or by a combination of two or more of these operations. In making the hollow T-shaped tenon, I prefer to use a gauge of metal comparable to that used in the blank. This sheet construction produces an oblong hollow-shaped post 4 which in combination with the web or rib 5 provides a T-shaped tenon 3. The tenon is then placed in a die and stamped to form the proper number, shape and size of lugs 6, see Fig. 3, to correspond to the number, shape and size of the holes 2 that have been punched in the blank 1. The lugs 6 are longer than the gauge thickness of the blank 1 so that when the tenon 3 and blank are assembled the lugs protrude a sufficient amount to form an adequately strong clinching rivet 7 as shown in Fig. 5.

The next operation is to place the backing of Fig. 5 in the combination of die fixtures shown in Fig. 1, wherein, 8 and 8' are the dies which when assembled have a cavity or mortise 9 which

is the counterpart of the tenon shown on the backing in Fig. 5. In the process of bending the backing member 1, the punch 10 is raised to an elevated position so that the tenon 3 can be inserted into the mortise 9 and then the punch strikes the backing a sharp descending blow with sufficient force to transform the member 1 of Fig. 5 so that in the end it conforms to the curved shape as shown in Fig. 6.

10 It will be understood that I provide different widths and lengths of backing for molars, for example, or for bicuspids or for any of the anterior teeth. In fact, I contemplate backings to be used for any tooth, upper or lower, that will be found in the human mouth. The number of lugs 6 of Fig. 3 is determined to some extent by the length of the backing and also to some extent by the masticatory stress which is exerted on the teeth in certain sections of the mouth.

15 In the construction of a bridge made according to this invention, I first prepare the metal framework to fit the articulation. Such a metal framework is shown in Fig. 10, wherein, by way of example only, I show at numeral 11 a Carmichael cast attachment or a three-quarter cast attachment for anchorage to an upper right natural cuspid tooth. The anchorage at the other end of the bridge consists of a full cast crown 12 to be cemented later to an upper right natural first molar. Between these abutment anchorages, I have assembled and firmly attached (preferably by soldering) two of my curved backings 13 and 13', which backings will later receive an upper right first bicuspid and an upper right second bicuspid plastic tooth made and produced in the following manner. As previously stated, the metal work of the bridge has been made to fit the articulation, then the bicuspid teeth are molded and formed to the bicuspid backings employing therefor any good working wax.

20 The wax teeth are shaped by carving for contour and cusp formation to the end that the wax teeth have harmonizing form and shape with the patient's remaining natural teeth, proper articulation with the cusps of the teeth in the opposite arch and proper adaptation to the gingival ridge. This work of carving is best facilitated by using accurately made models of the patient's mouth and which models are 25 mounted on a good articulator. After the wax teeth are formed and carved, the metal framework of the bridge, with the wax teeth in place, is removed from the model and invested in the manner commonly understood by those skilled 30 in the art. The wax composition, of the wax teeth, is eliminated from the mold by one of the commonly used processes whereby the space occupied by the wax becomes a void within the investment. The void or voids have the counter-conformation of the wax teeth so that they 35 become a mold into which one of the unpolymerized plastics is packed. For example, I may use a methyl methacrylate (acrylic) composition in certain desired colors or shades and pack these in the mold in a manner so that when 40 completely polymerized (cured) the finished plastic tooth will closely simulate the shade of the patient's natural teeth.

45 It will be understood that the mold cavities contain my curved backings in a manner whereby the inner surface of the curved member is exposed and the acrylic material is packed directly against it. Likewise the acrylic is packed against and around the tenon and over the incisal edge 50 and the proximal edges of the curved member.

so that the cured tooth will be adequately supported against the stresses and strains of mastication when in service in the mouth. Further, the acrylic tooth is rigidly anchored to the backing because it has been cured in a position directly on the backing and accordingly cannot be removed without virtually destroying or at least extensively mutilating it.

Bridges made according to my invention are "tailor-made" for the patient. They are strong, the plastic teeth are shaded and contoured for the individual patient, all of which goes to make a highly satisfactory restoration that is more thoroughly effective in function and with esthetic qualities that, so far as I am aware, have never been obtained heretofore.

For those dentists who may find it necessary, for one reason or another, to remove one of the plastic teeth from a bridge after it has been in service in the mouth or for the dentist who may not desire to make a bridge in the "tailor-made" fashion, I supply a full line of corresponding plastic teeth as articles of manufacture. The teeth, according to my invention, will be marketed in an assortment of lengths, widths and thicknesses, and in a variety of shades, colors or blends so that they can be used as the so-called interchangeable teeth in association with my special backings. It should be understood that such a line of teeth is contemplated to include both anterior and posterior teeth for the upper and lower dental arches of mankind. Such a posterior (bicuspid) tooth 14 is shown in the drawings in Figs. 7, 8 and 9. Fig. 7 is an exterior proximal view of the tooth wherein a shoulder 15 is shown near its occlusal or incisive end and where one of the proximal shoulders 16' of the backing-receiving recess can be seen. The mortise which is composed of the bore or hole 17 and the restricted slot 18 is shown in dotted lines. In Fig. 8, a lingual view of the bicuspid tooth is shown, wherein the shoulder near the occlusal or incisive end is shown at 15, the two proximal shoulders of the backing recess are shown at 16 and 16', the post bore or hole 17 is shown in dotted lines and the slot is shown at 18. In Fig. 9 a transverse section through the tooth, looking toward the gingival end thereof, illustrates the arcuate configuration of the backing recess.

Artificial teeth so formed may be readily applied to the tenon post of the backing and cemented thereto for permanent retention. In the preferred technique in which the acrylic teeth are joined with the bridge backings or framework in a molding operation, the teeth are permanently bonded to the backings and cannot be removed therefrom in an intact condition. The arcuate or concave form of the backings provides an acrylic tooth of unusual depth, which is advantageous for shade control and translucency. Furthermore, the construction from a labial point of view dispenses with an unsightly showing of the metal framework. Due to their arcuate formation, the individual backings may be flexed, if desired, to vary somewhat their standard widths, thus adapting the same readily to the dimensional characteristics of the teeth employed in connection therewith.

In view of the foregoing, it will be appreciated that bridges made in accordance with my invention overcome the shortcomings or defects of the prior art and provide marked improvements in dental bridge functioning, esthetics and oral hygiene.

I claim:

1. A backing for the mounting of artificial teeth comprising a plate having incisal, gingival and proximal edges, said plate possessing a deep substantially uniform arcuate curvature between its incisal and gingival edges in horizontal planes for relatively extended engagement with the lingual and proximal surfaces of an associated tooth and being straight and unbowed in planes parallel with its proximal edges, a plurality of relatively spaced vertically aligned openings formed in said plate in the central region thereof, a tenon post extending centrally and vertically of said backing, said post projecting outwardly and laterally from a tooth-mounting surface of said backing and formed along its outer longitudinal edge with an enlarged head, the latter being joined with a web of reduced cross-sectional thickness as compared with that of said head, and a plurality of spaced lugs integrally projecting from the inner vertical edge of the post web, said lugs being positioned in the openings of said backing and being of such length as to extend through and beyond said openings to provide ends adapted for clinching engagement with lingual surfaces of the backing, said post terminating at one end substantially evenly with the gingival edge of the backing and at its other end short of and in spaced relation to the incisal edge of said backing.

2. A backing for the mounting of artificial teeth comprising a plate having incisal, gingival and proximal edges, said plate possessing a deep substantially uniform arcuate curvature between the incisal and gingival edges thereof in planes passing horizontally therethrough for extended engagement with the lingual and proximal surfaces of an associated tooth and being substantially straight and unbowed in vertical planes passing therethrough between its proximal edges, the center of said plate being formed with an opening, a tenon post extending centrally and vertically of said backing between its incisal and gingival edges, said post projecting outwardly and laterally from a tooth-receiving surface of said backing and being formed along its outer longitudinal edge with an enlarged head, the latter being integrally joined with a web of reduced cross-sectional thickness as compared with that of said head, and lug means integrally projecting from the inner vertical edge of the post web, said lug means being positioned in the opening of said plate and being of such length as to extend through and beyond said opening to provide ends adapted for clinching engagement with lingual surfaces of the plate, said post terminating at one end substantially evenly with the gingival edge of the backing and at its other end short of and in spaced relation to the incisal edge of said backing.

3. A backing for the mounting of artificial teeth as defined in claim 2 and wherein the tenon comprises a sheet of material folded upon itself to form a hollow post head.

4. In a dental bridge, a framework having a tooth-receiving backing of arcuate configuration and formed from plate material of sufficient thinness to admit of flexing thereof to vary its effective width, a rigid tenon post extending longitudinally of the tooth-receiving surface of the backing from its gingival edge to a position adjacent to but short of its incisal edge, an artificial tooth joined with said backing, said tooth comprising a body composed of an acrylic plastic and having a recessed backing-engaging surface

on its lingual side, said surface conforming to the configuration of said backing and including incisal and proximal shoulders adapted for engagement with the corresponding edges of said backing, said surface extending to the plane of the gingival surfaces of the tooth body and terminating short of and in spaced relation to the incisal surfaces of said body, and a slot provided in said tooth body and opening to the recessed surface thereof to receive the tenon post of said backing, said slot conforming to the cross-sectional configuration of said post.

5. In a dental bridge, a framework having a tooth-receiving backing of arcuate configuration and formed from plate material of sufficient thinness to admit of flexing thereof to vary its effective width, a rigid tenon post extending longitudinally of the tooth-receiving surface of the backing from its gingival edge to a position adjacent to but short of its incisal edge, an artificial tooth joined with said backing, said tooth comprising a body having a recessed backing-engaging surface on its lingual side, said surface conforming to the configuration of said backing and including incisal and proximal shoulders adapted for engagement with the corresponding edges of said backing, said surface extending to

6 the plane of the gingival surfaces of the tooth body and terminating short of and in spaced relation to the incisal surfaces of said body, and a slot provided in said tooth body and opening to the recessed surface thereof to receive the tenon post of said backing, said slot conforming to the cross-sectional configuration of said post.
